14 Claims. (Cl. 210—31)

A very modern form of chromatography is the so-called "thin-layer" chromatography. The said name is based on the use of the adsorption agent in the form of a thin layer on an inert base. This arrangement possesses a number of known advantages as compared to the conventional adsorption column. According to the standard method the distance to be traversed by the solvent used as mobile phase for the chromatographic separation is limited by the dimensions of the apparatus. While this is of no significance for the separation of substance mixtures, the components of which have distinctly different migration velocities, the separation of substances having very similar migration velocities is only possible if a correspondingly large path of migration would be provided. Since the path of migration is always smaller than the distance to be traversed by the solvent, the separation of substances with very similar migration velocities thus requires a large distance to be traversed by the mobile phase and this requirement in its turn gives rise to the requirement for large, even very large apparatus dimensions. In paper chromatography, a known operating technique closely related to the said thin-layer chromatography, the above said disadvantage may be avoided, on the one hand by selecting the mobile phase e.g. such that it moves at least twice as quickly as the quickest component of the mixture of substances and on the other hand by virtually increasing the distance to be traversed by said mobile phase, that is to say allowing the mobile phase to flow beyond the area of the adsorption agent. This latter effect is most simply attained by a vertical arrangement of the paper, by a descending flow direction of the mobile phase and by dripping off from the lower edge of the paper. The solvent being the mobile phase is thus allowed to flow through the adsorption agent, the use of this arrangement being known as "run-through chromatography"; "run-through method" and "run-through principle" are synonymous expressions.

As known, the run-through principle considerably broadens the range of use of paper chromatography. An arrangement for the thin-layer chromatography analogous to the run-through paper chromatography is indeed conceivable, but complicated, and has thus not previously been described. It is, however, evident that a further improvement of the in fact already excellent separation chances of the thin-layer chromatography by means of a suitable arrangement for use of the run-through principle must further considerably increase the great practical advantage of thin-layer chromatography.

One of the objects of the present invention is a method for the selective performance of thin-layer chromatography

2

according to the run-through method or standard method, while another object of the present invention is an apparatus for performing the said new method. The method for thin-layer chromatography is performed in that mixtures of substances to be separated are applied along a starting line S on the thin layer, the solvent is allowed to flow from a solvent container B through a fluid bridge F onto the covered thin layer, the same is allowed to flow through this latter and, if desired, to flow out of the covered thin layer for the time required for further substance separation, whereupon the solvent can evaporate or drip off.

The apparatus which is surprisingly simple is characterized by that the thin layer used for the separation of the substances lies on a carrier plate T, is sealed off from the surrounding area by a cover plate D positioned parallel to the said carrier plate and by support or guide members positioned on two sides thereof, its front end being connected with a container B for the solvent by means of a fluid bridge F covered by the carrier plate and the end portion opposed to the front end being open or connected with the surrounding area by means of a fluid bridge.

When using the new apparatus of the present invention for run-through thin-layer chromatography, the proven rules for thin-layer and paper chromatography, well-known to the man skilled in the art, are advantageously followed with respect to the choice of adsorption agent and solvent, as well as the chromatogram loading. It is thus obvious that to separate substances which behave chromatographically very similarly, solvent systems will preferably be used, in which the substances to be separated move very slowly, when compared with the speed with which the solvent, i.e., the mobile phase, is moving.

Filter paper, for example, can be used as fluid bridge. It is, however, also possible to use another absorbent material or a narrow slit. The transport of the liquid fluid may take place by capillary forces, by gravity, centrifugal force or pressure. The solvent is thus, by way of example, transferred by the capillarity of the fluid bridge onto the thin layer and after flowing through the migration path, i.e., the portion of the thin layer covered by the cover plate, can evaporate or drip off, whereby this can take place either directly or across a fluid bridge, e.g., a filter paper adjacent the layer, which projects into the surrounding area. The apparatus is particularly simple with the thin layer in horizontal position and with evaporation from its uncovered, open end portion as shown in FIG. 5 of the enclosed drawings.

The support or guide members mounted longitudinally between the carrier and cover plates serve for sealing and must, more particularly at the junction of the fluid bridge with the layer, guarantee sufficient spacing between the layer and the cover plate to hinder solvent from flowing into the intermediate area by reason of capillarity. It is constructionally particularly simple to mount the cover plate on runners which project beyond the upper edge of the layer by 0.01 to 10 mm. A further appropriate solution consists in fixing the desired space between the cover plate and the carrier plate or thin layer by a guide rail.

The fluid container, carrier plate, cover plate and support or guide members are advantageously made of a chemically inert material, such as glass, metal, a synthetic substance or metallized synthetic substance; if desired, a combination of these substances may also be used.

The use of the new apparatus of the present invention is, however, not only restricted to cases in which one must use the run-through principle to attain separation. On the contrary, it is characteristic for the novel arrangement that it can generally also be employed wherever it suffices to use the usual thin-layer chromatographic standard device described by Stahl, "Archiv der Pharmazie," 292/64, 411 (1959). In such a case one can proceed by interrupting the chromatography when the solvent front has run through approximately the path from the starting line to the end of the cover plate (standard method). It is thus a particular characteristic of the said apparatus for thin-layer chromatography that it can be employed both in the run-through method and in the standard method. The chamber saturation which is so important according to the usual standardized apparatus of Stahl is hereby of no significance. The present invention thus excellently combines simplicity of apparatus with multiplicity of use.

The individual parts, the assembly, the process and, by means of examples, the use of an apparatus according to the invention will be described hereinafter, without in any way thereby limiting the nature, scope or application range of the invention.

The enclosed drawings help to illustrate the invention:

FIG. 1: Container B made of V4A steel for the mobile phase; in perspective view;

FIG. 1a: is a sectional view of the container of FIG. 1;

FIG. 2: Cut sheet for the filter paper F;

FIG. 3: Carrier plate T made of glass with thin-layer and bare edges;

FIG. 4: Cover plate D made of glass with runners and mounted filter paper F in perspective view;

FIG. 4a: is a sectional view of one edge of the cover plate of FIG. 4;

FIG. 5: Apparatus for thin-layer chromatography with selective use of the run-through or standard method in section; and

FIG. 5a: is a perspective view of the apparatus of FIG. 5.

ABBREVIATIONS CITED IN THE DRAWINGS

a, b, c, d, e, f, g, h=orientation aids, see text;
 B=Container for the mobile phase;
 D=Cover plate;
 F=Filter paper (=fluid bridge);
 G=Glass bands (=runners=support members);
 K=Clips, drawn diagrammatically;
 L=Holes for inserting polyethylene tubes;
 R=Tubes made of polyethylene for introducing the mobile phase and for pressure equalization;
 S=Starting line, along which the substance mixtures are applied on points;
 T=Carrier plate with thin-layer;
 U=Support being a cork ring.

A. Individual parts of the apparatus

(1) *Container B made of stainless steel (FIG. 1).*—It has a plane cut upper surface and serves as receptacle for the mobile phase. Two short polyethylene tubes R are inserted through two holes L in the side wall and bent upwards according to FIG. 1 (cross-section). The mobile phase will later be poured in through one of said tubes, the other one serving for pressure equalization (see below).

(2) *Filter paper F (FIG. 2).*—It transfers the mobile phase onto the layer. The part "efgh" is adapted to the inner profile of the container.

(3) *Carrier plate T made of glass comprising the thin-layer (FIG. 3).*—On two opposed edges such an amount of the layer is wiped off that the runners (see below) just fit on the bare strips. 15 mm. away from the front plate edge is the starting line S where the substances are to be applied (FIG. 3).

(4) *Cover plate made of glass with "runners" G (FIG. 4).*—Two plane-cut glass bands welded longitudinally onto the cover plate serve as runners. The height of the runners permits selective adjustment of the space between the layer and the cover plate; simultaneously, the runners act as sealing.

(5) *Six strong paper clips K.*—They serve to press the container B and the carrier plate T against the cover plate D (FIG. 5).

(6) *Support U.*—The same can have ring form, a cork ring, for example, being suitable (cf. FIGS. 4 and 5).

B. Assembly and method

25 The cover plate with the runners facing upwards is laid on the cork ring U, the filter paper is folded along the line "cd" (FIG. 2) and laid on the front side of the cover plate with the piece "abcd" downwards (FIG. 4). The paper should not touch the runners and the edge "ab" 30 should be slightly spaced away from the front edge of the cover plate (1-3 mm.). This position is provisionally fixed with a paper clip. The carrier plate with the layer and the substances to be chromatographed, which latter have already previous to assembly been applied on points 35 along the starting line S (FIG. 3), is now laid onto the cover plate in such a way that the bare strips come to rest on the runners and the front edge of the carrier plate exactly corresponds with the front edges of the runners. The carrier plate and the cover plate are now pressed together by four paper clips and the clip on the filter paper, which has now become superfluous, is removed. The upper part of the filter paper is bent along the connecting line "f" (FIG. 4) into vertical position and the clipped together plates are inverted so that the filter paper is now on the underside. As shown in FIG. 5, the container 40 B is clipped with two clips K under the cover plate in such manner that the vertically upright part of the filter paper reaches to the bottom of B and the horizontal part acts as sealing between the cover plate and the upper surface 45 of the container B. The container should lie close against the carrier plate. Mobile phase is poured in through a polyethylene tube, a momentary uniform wetting of the filter paper is attained by slight tilting and the arrangement can now be left alone. The mobile phase containing 50 the solvent evaporates after running through the layer protected by the cover plate on the still remaining strip (FIG. 5) sufficiently quickly to keep the chromatography as long as desired in action. If required, mobile phase is now on the underside. As shown in FIG. 5, the container 55 B is clipped with two clips K under the cover plate in such manner that the vertically upright part of the filter paper reaches to the bottom of B and the horizontal part acts as sealing between the cover plate and the upper surface 60 of the container B. The container should lie close against the carrier plate. Mobile phase is poured in through a polyethylene tube, a momentary uniform wetting of the filter paper is attained by slight tilting and the arrangement can now be left alone. The mobile phase containing 65 the solvent evaporates after running through the layer protected by the cover plate on the still remaining strip (FIG. 5) sufficiently quickly to keep the chromatography as long as desired in action. If required, mobile phase is now on the underside. As shown in FIG. 5, the container

Disturbances.—Variations of room temperature can sometimes (particularly with severe flow of air) lead to the mobile phase condensing on the cover plate. In such cases it suffices to warm the cover plate slightly by laying one's hand on it for a short time. So-called edge effects are avoidable with careful assembly.

C. Use

70 The arrangement described can, according to the invention, be used to separate difficultly and readily separable substance mixtures. The following table gives a number of examples and the conditions observed for separation. The adsorption agent is in all cases silicic gel for thin-layer chromatograms according to Stahl (Merck); the

space between the starting line and the end of the cover plate is 16.5 cm., the height of the runners is 1 mm.

What we claim is:

1. A method for the selective performance of thin-layer chromatography which comprises applying a mixture of substances to be separated along a starting line on a thin-layer, causing a solvent to flow from a solvent container through a fluid bridge onto the covered thin-layer, allowing the solvent to flow through said layer for the time required for substance separation.

2. A method for the selective performance of thin-layer chromatography which comprises applying a mixture of substances to be separated along a starting line on a thin-layer, causing a solvent to flow from a solvent container through a fluid bridge onto the covered thin-layer, allowing the same to flow through said layer and out of the covered thin-layer for the time required for further substance separation, an evaporation step being finally effected.

3. A method for the selective performance of thin-layer chromatography which comprises applying a mixture of substances to be separated along a starting line on a thin-layer, causing a solvent to flow from a solvent container through a fluid bridge onto the covered thin-layer, allowing the same to flow through said layer and out of the covered thin-layer for the time required for further substance separation, a dripping-off step being finally effected.

4. A method for the selective performance of thin-layer chromatography which comprises applying a mixture of substances along a starting line on a thin-layer, causing a solvent to flow from a solvent container through a fluid bridge onto the covered thin-layer, allowing the same to flow through said layer, out of the said layer and through a second fluid bridge to the outside area for the time required for further substance separation.

5. An apparatus for the performance of thin-layer chromatography in which a solvent is flowed through a thin-layer to which a mixture of substances has been applied

and separation of the components of the mixture is thus effected, which apparatus comprises a carrier plate bearing a thin-layer used for the separation; a container for the solvent; a fluid bridge constituting means for transporting the solvent from the solvent container to one end of the thin-layer; and a cover plate constituting means for isolating the thin-layer from the outside environment.

6. An apparatus as in claim 5, in which the end of the thin-layer opposite the fluid bridge connecting the solvent and thin-layer is connected to the surrounding environment through a second fluid bridge.

7. An apparatus according to claim 5, in which the fluid bridge constituting means for transporting the solvent from the solvent container to one end of the thin-layer is covered by the cover plate.

8. An apparatus as in claim 5, in which the container for the solvent is covered by the cover plate.

9. An apparatus as in claim 6, in which the fluid bridges and the container for the solvent are covered by the cover plate.

10. An apparatus as in claim 5, containing means for introducing the solvent into the solvent container from the outside area.

11. An apparatus as in claim 5, in which the cover plate has runners firmly attached to the bottom at the outer edges thereof, said runners having a thickness equal to or slightly less than the thickness of the said fluid bridge, which runners serve as support and guide members as well as means for isolating the said thin-layer from the outside environment.

12. An apparatus according to claim 5, in which the fluid bridge comprises filter paper.

13. An apparatus according to claim 5, in which the container for the solvent, the fluid bridge, and the carrier plate are pressed against the cover plate.

14. An apparatus for the performance of thin-layer chromatography in which a solvent is flowed through a thin-layer to which a mixture has been applied and separation of the components of the mixture is thus effected, which apparatus comprises a carrier plate bearing a thin-layer for the said separation; a container for the said solvent, said container being positioned adjacent to one end of the said carrier plate; a fluid bridge extending between the said solvent container and the solvent container end of the said thin-layer and constituting means for transporting the solvent from the solvent container to the said thin-layer; a cover plate having firmly attached to the bottom at the outer side edges thereof runners, said runners having a thickness equal to or slightly less than the thickness of the said fluid bridge, which runners serve as support and guide members as well as means for isolating the said thin-layer from the outside environment; said cover plate covering the container for the solvent, the fluid bridge and the carrier plate and constituting means for isolating from the surrounding environment the container for the solvent, the fluid bridge and the thin-layer; means for firmly pressing the cover plate against the container for the solvent and for pressing the runners of the cover plate against the outer side edges of the thin-layer side of the said carrier plate; and means for introducing the solvent into the solvent container and equalizing the pressure in the solvent container when the cover is in position.
